UNITED STATES PATENT OFFICE.

JOHN B. GORRELL, OF KENDALLVILLE, INDIANA, ASSIGNOR OF ONE-HALF TO HIRAM V. GORRELL, OF KENDALLVILLE, INDIANA.

LAWN-SPRINKLER.

No. 920,864.

Specification of Letters Patent.

Patented May 4, 1909.

Application filed November 23, 1908. Serial No. 463,987.

To all whom it may concern:

Be it known that I, JOHN B. GORRELL, a citizen of the United States, residing at Kendallville, in the county of Noble and State of Indiana, have invented certain new and useful Improvements in Lawn-Sprinklers; and I do declare the following to be a full, clear, and exact description of the invention, such as will enable others skilled in the art to 10 which it appertains to make and use the same.

This invention relates to improvements in lawn sprinklers and of that type adapted to produce a circular water spray.

One of the objects of the invention is the production of a simple lawn sprinkler having a base portion adapted to receive a stream of water through a cone-shaped inlet provided with a cone-shaped support arranged on the 15 base adapted to produce a spiral movement to the water when said water is flowing through the base portion and to produce a spray of the water.

In the accompanying drawings, Figure 1 is 20 a side elevation of my improved sprinkler, Fig. 2 is a horizontal sectional view, thereof, and Fig. 3 is a vertical sectional view.

In the accompanying drawings, the numeral 1 designates a base portion which is 25 formed with a centrally disposed upstanding cone-shaped lug or deflector 2, a circular flange 3 and a tangentially disposed nipple 4 having internal screw threads formed thereon. The nipple 4 communicates by a cone-shaped opening 5 with the chamber 6 and a 30 cone-shaped outlet member 7 is formed or screwed on to the circular flange 3, said support or outlet member being provided with an exhaust port 8.

In the operation of the device, the water 35 entering through the cone-shaped opening 5 will contact at 9 with the inner surface of the flange 3 and be given a rotary motion by said flange and a spiral motion by the cone-shaped lug or deflector 2, which spiral motion 40 will be intensified as the water passes up-

wardly in the cone-shaped support or outlet member 7 and escapes through the exhaust port 8, the cone-shaped outlet member 7 tending to concentrate the spirally rotating 50 particles of the water so that when said water escapes from the outlet member it will be distributed over a wide area in a very fine spray or mist.

From the foregoing description, taken in 55 connection with the accompanying drawings, the construction and operation of the invention will be readily understood without requiring a more extended explanation.

Various changes in the form, proportion 60 and the minor details of construction may be resorted to without departing from the principle or sacrificing any of the advantages of the invention as defined in the appended claims.

I claim as my invention:

1. A water sprinkler comprising a base portion having a circular flange formed thereon, a centrally disposed cone-shaped deflector arranged on the base portion from 70 within the circular flange, a cone-shaped outlet member arranged on the base portion and a nipple having a cone-shaped inlet communicating with the interior of the circular flange and the outlet member.

2. A water sprinkler comprising a base portion formed with a centrally disposed cone-shaped deflector and a circular flange arranged around the deflector having an inlet nipple with a cone-shaped inlet communicating therewith, said nipple being tangentially disposed on the circular flange, and a cone-shaped outlet member arranged on the circular flange.

In testimony whereof I have hereunto set 85 my hand in presence of two subscribing witnesses.

JOHN B. GORRELL
